DESIGN FOR A PLASTIC UNIT FOR USE ON HANDBAGS OR THE LIKE

Ida Jolles, New York, N. Y.

Application March 17, 1943, Serial No. 109,771

Term of patent 7 years

To all whom it may concern:

Be it known that I, Ida Jolles, a citizen of no country, but having declared my intentions of becoming a citizen of the United States of America, residing in the city of New York, county of New York, and State of New York, have invented a new, original and ornamental Design for a Plastic Unit for Use on Handbags or the like, of which the following is a specification, reference being had to the accompanying drawing, forming part thereof, wherein,

Figure 1 is an elevational view of a plastic unit for use on handbags or the like showing my new design, and,

I claim:

The ornamental design for a plastic unit for use on handbags or the like, substantially as shown.

IDA JOLLES.
